UNITED STATES PATENT OFFICE.

OSCAR W. JOHNSON, OF ROCKFORD, ILLINOIS, ASSIGNOR TO WARD PUMP COMPANY, OF ROCKFORD, ILLINOIS, A CORPORATION OF ILLINOIS.

PUMP.

1,121,588.

Specification of Letters Patent.

Patented Dec. 15, 1914.

Application filed December 6, 1913. Serial No. 805,076.

To all whom it may concern:

Be it known that I, OSCAR W. JOHNSON, a citizen of the United States, residing at Rockford, in the county of Winnebago and 5 the State of Illinois, have invented certain new and useful Improvements in Pumps, of which the following is a specification.

This invention relates to pumps, more particularly to valve structure thereof.

10 The valve structure of water pumps is subject to much wear and damage, for it is evidenced: that after length of use the valve or valve parts become corroded and as a result are inefficient in their actions, 15 also that foreign particles or obstructions often become lodged in the valve members so as to impair and even stop their actions. It is therefore desirous of providing valve structure of such a nature that the different 20 valve members may be easily removed from the pump for various needs. Also it follows that it is beneficial to construct the pump itself separate from the valve structure to allow greater latitude for removing 25 of the valve parts, and because the pump can be manufactured much easier separate as there is not the multitude of small operations inherent in valve structure; thus in the construction of gear pumps 30 great advantage is gained by building into the base of the pump a valve supporting structure, from which pump and base structure the valve supporting structure may be readily and easily removed without disturbing 35 the former members, and from which base the pump can be removed without disturbing the valve or base members.

The object of my invention therefore, is 40 to provide an improved pump and valve structure in which the valve structure may be easily removed from its operative position in the pump, for the purposes above set forth; and a further object is to provide the said valve casing detachably mounted 45 and to attach a conduit leading thereto, whereby the conduit can be removed from the pump structure without breaking its attaching or union connection with the said valve casing, by the integral removal of the 50 conduit and valve casing.

In the accompanying drawings: Figure

1 is a vertical sectional view through a gear-pump embodying my invention, as taken on the line 1—1 of Fig. 2. Fig. 2 is a plan sectional view as taken on the line 55 2—2 of Fig. 1. Fig. 3 is a sectional view looking at the under side of the base and valve structure, as taken on the line 3—3 of Fig. 1. Fig. 4 is a plan sectional view taken on the line 4—4 of Fig. 1. Fig. 5 is 60 a view similar to Fig. 4 but with the valve member moved to a position about to be withdrawn from the base.

A rectangular elevated base 6 supports a gear-pump and also forms an inclosure for 65 the valve structure. The base has an open side 7, the top 8 formed with a circular opening 9 therethrough, and lugs 10 extend into the base inclosure from opposite sides thereof, reaching into the top opening 9 and 70 spaced from the top 8 of the base. A gear-pump 11 is mounted on base 6, secured to the top 8 thereof by bolts 12 extending through a flange on the inlet side of the gear-pump and through lugs 10 at the outer 75 side of the top opening 9. The inlet 13 of the pump opens into the base inclosure and the casing therefor is rectangular in shape, extending diametrically across top opening 9. A valve casing 14 of a rectangular shape conforming to the shape of the inlet 13 but its ends curved with opening 9, is located within the base and the opening 9 is adapted to abut the under face of the inlet casing, the ends of said valve casing 80 lying intermediate the extensions of lugs 10 and said inlet casing; and set-screws 15 are carried in lugs 10, their heads down, and are adapted to engage the ends of valve casing 10 and when screwed up, to hold said casing seated tight upon the under face of the inlet casing of the pump. The valve casing has a central bore 16 into the lower end of which is screwed a supply pipe section 17. A valve 18 closes bore 16, seated upon the top of valve casing 14, has ribs 19 for guiding it during rising movement, and is adapted to be limited in its rising movement by a cross-pin 20 carried above the valve by the inlet casing 13. By operation of the rotors of the pump in the proper direction, valve 18 will be raised by suc-

tion and liquid drawn through pipe 17 and into the pump chamber, this being a common valve movement.

When it is desirous of removing the valve or of gaining access thereto, it may be so done without deranging any of the pump casing or base, by loosening set-screws 15 freeing the valve casing 14 and allowing same to be turned a quarter turn (as shown 10 in Fig. 5) so that it may avoid the extensions of lugs 10 and be lowered into the open base inclosure, there to be freely accessible or to be removed as the necessity demands. It will be observed that the 15 pump may be removed without affecting any of the base or valve elements. It will also be noticed that the pipe-section or conduit 17 is in a union with the valve casing, and to remove said conduit said union need 20 not be broken, since the removal may be made by the detaching of the valve casing, whereby both conduit and casing will be integrally removed.

I claim as my invention:

25 1. The combination with a pump base and a pump mounted thereon, of a valve casing carried by the pump base, a valve carried by the valve casing in communication with the pump, and fastening means for holding 30 the valve casing in said position and to allow the valve casing to be removed from said position without the removing of said fastening means.

35 2. In a pump, a valve casing, a valve carried thereby, and fastening means for holding the valve casing in a position with its valve in communication with the pump, said fastening means being movable without being moved from the pump structure to 40 release said valve casing to allow same to be withdrawn from the pump.

3. In a pump, a valve casing, a valve carried thereby, fastening means for holding the valve casing in operative position and 45 being movable but not from its support, to allow the valve casing to be removed.

4. A pump having a port opening, a valve casing carrying a valve in communication with said port opening, and fastening means 50 for maintaining the valve casing in such position, said means including a screw member adapted when tightened to lock the casing in position and when loosened but not removed, to allow the valve casing to be removed from its said position.

5. In a pump having a port opening, fixed lugs spaced from the face thereof, a valve casing having portions located between the 60 said lugs and the port face, and a screw carried by one of said lugs to hold the valve casing fixed against said port face.

6. In a pump having a port opening, fixed lugs spaced from the face thereof, a valve casing having portions located between the

said lugs and the port face, and fastening 65 means carried by one of said lugs for holding said valve casing in position, said valve casing when the fastening means are released, being removable from between the said lugs and port face. 70

7. The combination with a casing having two openings therein, of a pump attached thereto and having a port opening communicable with one of said casing openings, a valve mounted within said casing and having a valve in communication with said port opening whereby the valve is inaccessible from the remaining casing opening, and fastening means for securing the valve casing in said position and to allow when loosened, 75 the valve casing to be moved to a position accessible through the said remaining casing opening.

8. The combination with a casing having an opening therein, of a pump attached to 85 the casing and having a port opening communicating with said casing opening, a valve casing carrying a valve in communication with the port opening, and fastening 90 means carried by the casing for holding the valve casing in said position, the valve casing being removable from said position by moving but not removing the fastening means from their carried position.

9. A pump structure having a circular 95 opening communicating with a pump port opening, a valve casing adapted to be received into said circular opening, and movable fastening means extending into said circular opening for holding said valve casing in operative position, said valve casing being removable from its said position by rotary movement thereof to withdraw parts thereof from said fastening means. 100

10. A pump structure having a circular 105 opening communicating with a pump opening, a valve casing adapted to be received into circular opening, and fastening means within close proximity of said circular opening and to be associated with said valve casing to hold same in its operative position, said fastening means including a member movable into engagement with the valve casing, whereby upon disengagement of said member the valve casing may be moved rotatably in said circular opening to be entirely freed from said fastening means. 110

11. A pump structure having a port opening, fixed lugs spaced opposite the face portion of said opening, a valve casing having 120 portions thereof located intermediate said lugs and face portion of said opening, and fastening means carried by said lugs to hold said valve casing fixed in position, the valve casing when said fastening means are loosened, being movable from intermediate said lugs and port face opening. 125

12. The combination with a casing, of a

pump structure fastened thereto and having a port opening communicating with the casing interior, a valve casing located within said casing and having a valve in communication with said port opening, and fastening means for holding said valve casing fixed in said position, the fastening means being carried in a fixed position but being movable to engage and hold the valve casing in its said positions and also being mov-

able but not removable to allow the valve casing to be removed.

In testimony whereof I have hereunto set my hand in presence of two subscribing witnesses.

OSCAR W. JOHNSON.
